UNITED STATES PATENT OFFICE.

FREDERICK OLIVER, OF NORTHAMPTON, MASSACHUSETTS, ASSIGNOR TO
BELDING BROTHERS & CO., OF SAME PLACE.

DESIGN FOR HOSEIERY.

SPECIFICATION forming part of Design No. 21,326, dated February 2, 1892.

Application filed December 5, 1891. Serial No. 414,168. Term of patent 3½ years.

To all whom it may concern:

Be it known that I, FREDERICK OLIVER, a citizen of the United States, residing at Northampton, in the county of Hampshire and State 5 of Massachusetts, have invented and produced a new and original Design for Hosiery, of which the following is a full, clear, and exact description, reference being had to the accompanying drawing, forming a part thereof, and 10 which represents a plan view of a portion of hose decorated in accordance with my design.

The leading feature of the design consists in the panels A, arranged at distances apart and having a ribbed appearance, and the par-

allel chain-like panels B, separating or spacing the ribbed panels. In detail the panels A simulate a corrugated or ribbed surface, and the panels B simulate open or lattice work, the prominent feature of the latter panels being a continuous chain-like open-work figure a.

I claim—

A design for hosiery, substantially as herein shown and described.

FREDERICK OLIVER.
